UNITED STATES PATENT OFFICE.

JOHN HOLTZMAN AND MORRIS KOVER, OF NEW YORK, N. Y.

COMBINED SAFETY-RAZOR AND RAZOR-BLADE SHARPENER.

1,170,754.

Specification of Letters Patent.

Patented Feb. 8, 1916.

Application filed March 29, 1915. Serial No. 17,718.

To all whom it may concern:

Be it known that we, JOHN HOLTZMAN and MORRIS KOVER, the former a subject of the Emperor of Russia and the latter a citizen of the United States, and residents of the city of New York, in the county of New York and State of New York, have invented a certain new and useful Combined Safety-Razor and Razor-Blade Sharpener, of which 10 the following is a specification.

This invention relates to safety razors, and its principal object is to provide a simple, inexpensive, efficient, and improved safety razor.

15 Another object is to provide an efficient and improved safety razor having combined therewith simple, inexpensive, efficient, and improved means for sharpening the razor-blade thereof.

20 Other objects and advantages will hereinafter appear.

In the accompanying drawings, Figure 1 shows a general end view of the safety razor. Fig. 2 is a side elevation of the razor shown 25 in Fig. 1. Fig. 3 is a plan view of the razor showing its razor-blade and guard turned around about their axes. Fig. 4 is a view similar to Fig. 3, but showing the guard removed from the razor blade. Fig. 5 is an 30 end elevation showing the razor converted into a stropping machine for its blade. Fig. 6 is a fragmentary sectional elevation similar to Fig. 5. Fig. 7 is an end elevation of the strap guide. Fig. 8 is a side elevation 35 of the strap guide.

Upon a handle 1 is fixed a frame 2 comprising a cross-bar 3, to the center of which said handle is secured, and posts 4, 5 located at the ends of the cross-bar. At the upper 40 extremities of the posts 4, 5 is rotatably mounted a shaft 6 perpendicularly to the handle 1 by means of its journals 7, 7' fitting in bearings 8 in said posts. The middle portion of shaft 6 is undercut, leaving this part 45 thereof semicircular in cross section and forming projections 10 at the ends of the shaft, whereby a double-edged razor-blade 11 provided with notches 12 at its extremities to fit over the projections 10 may be seated upon the flat portions 13 of said shaft. In this position of the razor-blade 11 its 50 longitudinal center line coincides with the longitudinal axis of shaft 6, and upon securing the blade to said shaft, by means of a screw 14 passing through a centrally located

opening 15 in the blade and threading into the shaft, the blade and shaft may be swung or completely rotated around their joint axes. An independent guard 16 for the razor-blade 11 is provided with a centrally located opening 17, adaptable to fit the shank of screw 14, and at the extremities of said guard are formed notches 18 the sides 19, 20 of which are adapted to bear against the shaft projection 10, whereby said guard may 60 be placed upon and alined in proper relation with the blade 11 and by tightening of the screw 14 against the guard it may be firmly secured to said blade and turned around therewith about the axis of shaft 6. 70 Preferably, the opening 17 in guard 16 is made to extend slightly in elongated form toward one side of the guard whereat it joins with a circular opening 21 having a diameter adaptable to pass over the head of screw 14, and the notches 18 likewise extend toward the same side of the blade. By means of this construction the guard 16 may be removed from the razor blade 11 and entirely from the machine by unthreading the 80 screw 14 but partially and shifting the guard to aline the opening 21 with the screw and then lifting the guard off, and in a reverse manner the guard may be replaced upon the blade and secured in position, 85 whereby the ready removal and replacement of the guard for cleaning the machine and for purposes to be hereinafter noted is facilitated. The journal 7' of shaft 6 is threaded and projects beyond the post 5, 90 and a knurled thumb-nut 23 threading over said projecting journal is adapted to tighten against the post 5 to thereby lock the shaft 6 with the razor blade 11 and guard 16 against rotation, in whichever position said 95 blade and guard may chance to be in. Thus as shown in Fig. 3 the blade 11 with its guard 16 are locked in a situation exactly opposite to their normal position, Fig. 1, to bring the guard 16 on top for facilitating its removal or replacement, and upon slightly unthreading the nut 23 and swinging the blade and guard half of a revolution they are restored to the normal or shaving 100 position shown in Fig. 1 perpendicularly to the handle 1, in which position the nut 23 may be tightened and the blade and guard securely locked against rotation. It will be evident that, in a like manner, the blade 11 and guard 16 may be adjusted to be disposed 105 110

and locked at any angular position, as indicated by the dash and dot lines, Fig. 1, and such setting of the blade with its guard at an angle to the shaving handle 1 will be 5 frequently found very convenient for shaving.

When it is necessary to sharpen the edges of razor-blade 11, the nut 23 may be partially unthreaded, the guard 16 removed, 10 and the screw 14 tightened against the blade to firmly secure it directly to the shaft 6, with which it is now free to rotate or swing about their joint axes. The shaft-journal 7 projects beyond the post 4 and carries a crank 24 which is disposed parallelly to the blade 11 and is provided at its extremity with a pin 25. Directly below the shaft 6 and parallelly thereto is mounted a roller 26 by means of journals 27, 27' thereof fitting in bearings 27 in the posts 4, 5, and said journals project slightly beyond said posts. The journal 27 carries a crank 29 having at its end a slot 30 adaptable to receive the crank-pin 25. After the razor-blade 11 has been rendered free to swing, the next step in the operation is to insert the crank-pin 25 into the slot 30 of crank 29 as shown in Fig. 5. A strap-guide 31 is provided, Fig. 8, comprising a pair of parallel 20 supports 32 held together by means of a pair of parallel guiding rods 33 riveted in ears 34 formed at the extremities of the supports. Said strap-guide is adaptable to be mounted upon the frame 2 of the safety 30 razor in the manner shown in Figs. 5, 6, and the operator may now guide it into this position by means of the projecting journals 7, 27 and 7', 27' being passed through the slots 34^a in supports 32. The operator then passes 40 a strap 35 around the roller 26 and places the ring shaped extremity 36 of the handle 1 over a hook 37 rigidly secured to a fixed object 38, whereupon the safety razor as shown in Fig. 1 is now converted into a 45 sharpening machine as shown in Fig. 5 for its razor-blade 11 and is thus rendered ready for stropping or sharpening the razor-blade edges 39.

When sharpening the razor-blade 11, the 50 operator alternately pulls at the rings 40, provided at the extremities 41, 41' of strap 35, so that said extremities move toward and away from the machine. As the strap extremity 41' is pulled the strap 35 rocks the 55 roller 26 and thereby causes the crank 29 to actuate the crank 24 to dispose the blade 11 in the position shown in Fig. 5, whereby as the strap extremity 41' travels away from the machine one side of each razor-edge 39 60 bears against the strap and undergoes sharpening. And as the strap extremity 41 is pulled an exactly opposite operation takes place and the roller 26 and cranks 29, 30 first cause the blade 11 to be disposed to an 65 opposite position, shown in Fig. 6, so that as

the strap extremity 41 recedes from the machine the remaining diagonally opposite sides of the razor edges 39 bear against the strap and undergo sharpening. In this manner the alternate pulling of the strap extremities 41, 41' oscillates the razor-blade 11 about its axis and causes the diagonally opposite sides of its edges 39 to alternately bear against the moving strap surface until the razor edges 39 become thoroughly sharpened. During the stropping operation the strap portions adjacent the blade 11 are maintained parallel to each other by being passed outside of the guiding-rods 33, Fig. 6, or inside of said rods as indicated by the 80 dash and dot lines, Fig. 7, depending upon the different tendencies of operators in pulling of the strap-extremities. After sharpening of the razor-blade has been completed, the safety razor may be readily restored to 85 its normal or shaving condition by unhooking the handle-extremity 36, removing the strap 35 and strap-guide 31, and disconnecting the cranks 24, 29. The guard 16 may be then replaced upon the blade 11 and swung therewith to the proper position for shaving and then locked in place by tightening the adjustment nut 23. A spring detent 42 on roller 26 bears against a burr 43 on post 5 to insure maintaining of said roller with the 90 crank 29 out of the way during shaving, in the position shown in Fig. 1.

Variations may be resorted to within the scope of the invention, and portions of the improvements may be used without others. 100

Having thus described our invention, we claim:

1. A safety razor having the combination with a handle, of a fixed and rigid frame thereon, of a double-edged razor blade pivoted between its edges in said frame, a guard for said blade adaptable to be removed, mechanism for sharpening said blade when in pivoted state, and means to adjust said blade and maintain it locked at any angular shaving position. 105

2. A safety razor having the combination with a handle, and a frame thereon, of a razor blade pivoted in said frame, a removable guard for said blade, mechanism for sharpening said blade when in pivoted state, and means to adjust said blade and maintain it locked at any angular shaving position. 115

3. A safety razor having the combination with a handle, of a fixed and rigid frame thereon, of a razor blade pivoted in said frame, a removable guard for said blade, mechanism for sharpening said blade when in pivoted state, and means to adjust said blade and guard at any angular shaving position. 120

4. A safety razor having the combination with a handle, of a fixed and rigid frame thereon, of a razor blade pivoted to rotate 125

- in said frame at its shaving position, a guard for said blade, mechanism for sharpening said blade when in rotatable state, means to adjust said blade and guard in shaving position, and means for removably connecting said guard with and disconnecting it from said blade.
5. A safety razor having the combination with a handle, of a fixed and rigid frame thereon, of a shaft pivoted in said frame, a double-edged razor blade secured between its edges to said shaft, a guard adaptable to be removably connected to and disconnected from said blade and shaft, mechanism for sharpening said blade when in pivoted state, and means to adjust said blade and guard in shaving position.
6. A safety razor having the combination with a handle, and a frame thereon, of a shaft pivoted in said frame, a double-edged razor blade secured between its edges to said shaft, a guard adaptable to be removably connected to and disconnected from said blade and shaft, guiding means on said shaft for alining said guard in proper relation to said blade, and means to adjust said blade and guard at any angular position about the axis of said shaft.
7. A safety razor having the combination with a handle, and a frame thereon, of a shaft pivoted in said frame, a razor blade secured to said shaft, a guard adaptable to be removably connected to and disconnected from said blade and shaft, and means to adjust said blade and guard at any angular position about the axis of said shaft.
8. A safety razor having the combination with a handle, and a fixed frame thereon, of a double-edged razor blade pivoted between its edges in said frame, means to adjust said blade and maintain it locked at any angular position, a roller mounted in said frame, a strap adaptable to be passed around said roller, means connecting said roller with said blade whereby rocking of said roller by pulling the ends of said strap oscillates said blade to sharpen its edges against said strap, and said handle having means for securing it to a fixed member during stropping.
9. A safety razor having the combination with a handle, and a fixed frame thereon, of a razor blade pivoted in said frame, means to adjust said blade and maintain it locked at any angular position, a roller mounted in said frame, a strap adaptable to be passed around said roller, means connecting said roller with said blade whereby rocking of the roller by pulling the ends of said strap oscillates said blade to sharpen its edge against said strap, and means for securing said handle to a fixed member during stropping.
10. A safety razor having the combination with a handle, of a shaft pivoted in said frame, a double-edged razor blade pivoted in said frame, a guard for said blade, means to adjust said blade and guard in shaving position, means for removably connecting said guard with and disconnecting it from said blade, a roller mounted in said frame, a strap adaptable to be passed around said roller, means connecting said roller with said blade whereby rocking of said roller by pulling the ends of said strap oscillates said blade to sharpen its edges against said strap, and said handle having means for securing it to a fixed member during stropping.
11. A safety razor having the combination with a handle, and a fixed frame thereon, of a razor blade pivoted in said frame, a guard for said blade, means to adjust said blade and guard in shaving position, means for removably connecting said guard with and disconnecting it from said blade, a roller mounted in said frame, a strap adaptable to be passed around said roller, means connecting said roller with said blade whereby rocking of the roller by pulling the ends of said strap oscillates said blade to sharpen its edges against said strap, and means for securing said handle to a fixed member during stropping.
12. A safety razor having the combination with a handle, and a frame thereon, of a shaft pivoted in said frame, a double-edged razor blade secured between its edges to said shaft, a guard adaptable to be removably connected to and disconnected from said blade and shaft, means to adjust said blade and guard in shaving position, a roller mounted in said frame, a strap adaptable to be passed around said roller, a strap guide adaptable to be mounted upon said frame, cranks connecting said roller with said shaft whereby rocking of the roller by pulling the ends of said strap oscillates said blade to sharpen its edges against said strap, and said handle having means for securing it to a fixed member.
13. A safety razor having the combination with a handle, and a fixed frame thereon, of a shaft pivoted in said frame, a razor blade secured to said shaft, a guard adaptable to be removably connected to and disconnected from said blade, means to adjust said blade and guard in shaving position, a roller on said frame, a strap adaptable to be passed around said roller, means connecting said roller with said blade whereby rocking of the roller with said strap oscillates said blade to sharpen its edge against said strap, and means for securing said handle to a fixed member during stropping.
14. A safety razor having the combination with a handle, and a fixed frame thereon, of a razor blade pivoted in said frame, means to adjust said blade in shaving position, a roller mounted on said frame, a strap

adaptable to be passed around said roller, means connecting said roller with said blade whereby rocking of said roller by pulling both ends of said strap oscillates said blade to sharpen its edge against said strap, and means for securing said handle to a fixed member during stropping.

15. A safety razor having the combination with a handle, and a frame thereon, of a razor blade pivoted in said frame, means to adjust said blade in shaving position, a roller mounted on said frame, a strap adaptable to be passed around said roller, a strap guide adaptable to be mounted upon said frame, means connecting said roller with said blade whereby rocking of said roller by pulling both ends of said strap oscillates said blade to sharpen its edge against said strap, and means for securing said handle to a fixed member during stropping.

16. A safety razor having the combination with a handle, of a fixed and rigid frame thereon, of a double-edged razor blade rotatably pivoted between its edges in said frame at its shaving position, mechanism for sharpening said blade when in ro-

tatable state, and means to lock said blade against rotation in shaving position.

17. A safety razor having the combination with a handle, of a fixed and rigid frame thereon, of a rotatable razor blade pivoted in said frame and adaptable to rotate therein for a complete revolution, mechanism for sharpening said blade when in rotatable state, and means to lock said blade against rotation in shaving position.

18. A safety razor having the combination with a handle, and a fixed frame thereon, of a razor blade pivoted to rotate in said frame, a removable guard for said blade, mechanism for sharpening said blade when in rotatable state, and means to lock said blade and guard in shaving position.

Signed at the city of New York, in the county of New York, and State of New York, this 24th day of March, A. D. 1915.

JOHN HOLTZMAN,
MORRIS KOVER.
